UNITED STATES PATENT OFFICE.

EUGENE H. RYERSON, OF WORCESTER, MASSACHUSETTS, ASSIGNOR TO HAMBLIN & RUSSELL MANUFACTURING COMPANY, OF WORCESTER, MASSACHUSETTS, A CORPORATION OF MASSACHUSETTS.

EGG-WHIP.

1,268,284.

Specification of Letters Patent.

Patented June 4, 1918.

Application filed March 16, 1918. Serial No. 222,803.

To all whom it may concern:

Be it known that I, EUGENE H. RYERSON, a subject of the King of England, residing at Worcester, in the county of Worcester and 5 State of Massachusetts, have invented a new and useful Egg-Whip, of which the following is a specification.

This invention relates to an egg whip, batter beater, or the like, and the principal objects thereof are to provide a construction having maximum efficiency for the above-mentioned purposes, and at the same time so constructed that it will serve as a spoon for 10 handling eggs, vegetables or other articles, and also to provide a construction in which, although made of wire so as to be light and easily manipulated, it will have a maximum of strength and durability and no parts likely to become unfastened or otherwise 15 loosened in the use of the device and one easily cleaned.

Further objects and advantages of the invention will appear hereinafter.

Reference is to be had to the accompanying drawings, in which—

Figure 1 is a plan of a preferred embodiment of this invention;

Fig. 2 is a side elevation looking in the direction of the arrow 2 shown in Fig. 1, 20 and

Fig. 3 is an end view as indicated by the arrow 3 in Fig. 2.

The device is shown as provided with a handle made up of a piece of sheet metal 25 10 wound around the butt ends of the wires making up the blade of the beater and soldered in position around their ends, and provided with a wire 11 coiled around the same and soldered in position thereto. This 40 makes a flat handle of a durable kind all metallic and sufficiently rough on the outside so that it is not likely to slip in the hand.

The main portion, bowl or blade, of the device comprises a plurality of wires 12 and 45 13, preferably an odd number. The ends of these wires are arranged in a plane and pass into and all the way through the sheet metal member 10 so that they terminate at the end of the handle, not shown. I have 50 designated these wires by two numerals because the wire 13, although having two ends entering the handle at its opposite sides, is

in a single piece and constitutes the border or edge of the device. It is of a loop-shaped form and forms the top of the article.

Each of the wires 12 extends through the handle in the same way between the two ends of the wire 13 and is co-extensive therewith at that point, but at the other end it extends only to the loop-shaped end of the 60 wire 13 to which it is fastened by being soldered, welded or otherwise secured to it.

In the preferred form of the invention shown these wires 12 are made substantially straight throughout the principal part of 65 their length, but are slanted downwardly away from the plane of the center of the handle, those at the center of the article being slanted more than those near the sides. But at a point near their ends they are all 70 curved upwardly and inwardly except the center one which does not have to be curved inwardly or sidewise but is curved upwardly. Their extreme ends at 14 are all brought into contact with the center of the 75 loop of the wire 13 and secured in the present instance to the outside surface of that wire by means of solder, or by being welded to it. The treatment to which they are subjected in fastening them embeds them somewhat in the wire so that they are not easily pushed sidewise by coming into contact with any obstacle.

On account of the shape given the various wires, it will be seen that the egg whip as a 85 whole is spoon-shaped so that it can be used for taking boiled eggs out of hot water, or in fact for lifting vegetables and other articles. Consequently it serves the purpose of a spoon which, being of skeleton form, is 90 instantly drained. Its principal purpose, however, is to be used as an egg whip in the ordinary way, and its utility for this purpose is not reduced by the spoon shape which is given it. On the contrary, it is 95 rather increased because the edge wire 13, which may be made larger and more rigid than the others, is located right in front of the next wire 12, and the second wire 12 is offset only a little from it when the article 100 is used on an ordinary beater or whip. Another advantage of the open sided spoon shape is that the inside portion can be reached very readily for cleaning, this being

especially useful on account of the frequent use of the article for beating eggs and batter.

Although I have illustrated and described only a single form of the invention, I am aware of the fact that modifications can be made therein by any person skilled in the art without departing from the scope of the invention as expressed in the claims.

10 Therefore I do not wish to be limited to all the details of construction herein shown and described, but what I claim is:—

15 1. As an article of manufacture, an egg whip comprising a blade or bowl with a 20 pressed center and its sides substantially in a plane raised from said center, made up of a plurality of wires, the wires located between the side ones being connected with the side ones at one end to form a handle, and 25 having their outer ends secured to the outer side of the outer wire at the loop end thereof in contact with each other along its outer surface.

25 2. As an article of manufacture, an egg whip consisting of a handle and a plurality of wires extending from the end thereof, their opposite ends all being connected together at one point, said wires being straight throughout most of their length, separated 30 at intermediate points and curved so as to constitute a blade or bowl of concave form, and by reason of their long straight portions being sufficiently flexible to constitute an efficient egg whip.

35 3. As an article of manufacture, an egg whip comprising a blade or bowl made up of a plurality of wires, one extending around and constituting the edge of the blade and the others being substantially contained 40 within the boundaries thereof and extending from one end to the other and all being rigidly connected with each other at their outer ends and embedded in and secured to the outer side of the first named wire.

45 4. As an article of manufacture, an egg whip comprising a blade or bowl made up of a plurality of wires, one extending from

the handle on one side around the blade to form a loop and back to the handle on the other side, its two ends being brought into 50 parallel position and spaced apart and the other wires each having one end located in a plane between the two ends of the first named wire and permanently secured thereto, their outer ends being secured to the first 55 named wire at the loop end thereof.

5. As an article of manufacture, an egg whip comprising a blade or bowl made up of a plurality of wires, one extending from the handle on one side around the blade to 60 form a loop and back to the handle on the other side, its two ends being brought into parallel position and spaced apart and the other wires each having one end located in a plane between the two ends of the first 65 named wire and permanently secured thereto, their outer ends being secured to the first named wire at the loop end thereof, in contact with each other along the outer surface of the loop, all the wires being curved to 70 bring the blade into concave form near the end.

6. As an article of manufacture, an egg and batter whip comprising a concave blade made up of a plurality of wires curved near 75 their ends to produce a concave bowl form and having their shanks substantially straight and brought together into a plane at the handle end.

7. As an article of manufacture, an egg 80 and batter whip comprising a concave blade made up of a plurality of wires curved near their ends to produce a concave bowl form and having their shanks substantially straight and brought together into a plane 85 at the handle end to form a flat handle, a sheet metal member surrounding the ends of said shanks and fastened to them, and a wire wound around the sheet metal member to furnish the gripping surface for said 90 handle.

In testimony whereof I have hereto affixed my signature.

EUGENE H. RYERSON.
